UNITED STATES PATENT OFFICE.

ERWIN MAURER, OF JAMAICA, NEW YORK.

BROODER.

1,295,346.

Specification of Letters Patent. Patented Feb. 25, 1919.

Application filed December 13, 1917. Serial No. 206,910.

To all whom it may concern:

Be it known that I, ERWIN MAURER, a citizen of the United States, residing at Jamaica, Long Island, in the county of Queens and State of New York, have invented certain new and useful Improvements in Brooders, of which the following is a full, clear, and exact specification.

This invention relates to brooders, and has for its object to provide a structure of this kind made in detachable parts, whereby it may be quickly set up for use or knocked down for shipment. Another object is to increase the capacity of the brooder by providing a plurality of compartments arranged one above the other.

It is also the aim of the invention to provide improved means for heating and ventilating the several compartments of the brooder, and to equip each compartment with a separate runway which is exposed to the outside air. A further object is to construct a brooder of a considerable number of comparatively small parts so that if one or more of them becomes broken or lost they may be replaced at small expense. Other objects will appear as the description proceeds.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views;

Figure 1 is a side elevation of a brooder constructed in accordance with this invention, part of the heating apparatus being broken away for the sake of clearness.

Fig. 2 is a plan view of the brooder.

Fig. 3 is a transverse vertical section taken on the line 3—3 of Fig. 2.

Fig. 4 is an inside elevation of one end of the brooder, showing more particularly the hinged door to the tunnel, and the grooves to receive the combined roof and floor members.

Fig. 5 is a section on the line 5—5 of Fig. 4, showing the tongue and groove connection between the two sections of the end member, and the interlocking connection between the upright portions of the combined floor and roof members, and the end member.

Fig. 6 is a broken detached view of the cover for the top compartment of the brooder.

Fig. 7 is a broken detached view of the tunnel which extends through the brooder from end to end.

Fig. 8 is a central vertical section through the brooder and tunnel, showing more particularly the dampers for controlling the admission of heated air to the several compartments of the brooder.

Fig. 9 is a transverse vertical section through the tunnel alone, showing the thermostatic controlling means for the dampers.

Fig. 10 is a longitudinal section taken on the line 10—10 of Fig. 3, showing more clearly the arrangement of the combined floor and roof members and the wire partitions between them for subdividing the compartments formed thereby.

Fig. 11 is a detailed view of one of the combined floor and roof members.

Fig. 12 is a broken side elevation of the end of the peak of a roof of modified construction having means for connecting an extension roof where it is desired to enlarge the roof, and

Fig. 13 is a section on the line 13—13 of Fig. 12.

The brooder has end members, each consisting of two supplemental portions 1 and 2 having tongue and groove connection at 3. The outer edges of the sections 1 and 2 are preferably stepped, as at 4, and their inner edges are cut away to form a door opening 5 which is normally closed by a door 6 hinged at 7 at one edge and preferably provided with a latch 8, Fig. 4, at its other edge. On the inside of the end member 95 there are formed horizontal grooves 9 in line with the several steps 4, said grooves extending from the door opening 5 to the outer edges of the sections 1 and 2 at the bases of said steps.

Between the end members and in line with the door openings 5 therein, there extends a peaked tunnel 10 which is made in two parts having tongue and groove connection 11 along the peak. The sections of the tunnel are provided with outstanding slotted ears 12 adapted to connect with headed lugs 13 on the inner faces of the sections 1 and 2 of the end members for retaining the parts in assembled relation. These ears 12 are preferably arranged near the top and bottom of each section of the tunnel, it being

noted that the peak of the tunnel extends some distance above the door openings 5 in the end members.

The space between the end members and outside of the tunnel is divided up into compartments by means of combined floor and roof members 14 which are in the form of flat plates the ends of which engage the grooves 9 in the end members. At the inner edge of each of the combined floor and roof members there is an upstanding flange 15 having notches 16 to connect with headed lugs 17 on the outer surface of the tunnel. After the members 14 are inserted in the grooves 9, the headed lugs 17 are sprung into engagement with the slots 16 in the flanges 15, whereby the members 14 are retained in position, as shown in Figs. 3 and 10. The lateral edges of the downwardly extending portions 18 at the front corners of the member 14 are adapted to engage grooves formed by rebent portions 19 at the ends of the steps 4 of the end members, as best illustrated in Fig. 5. The compartments thus formed are inclosed at the outside by curtains 20. Beyond said curtains runways are inclosed by wire screens 21, attached in any suitable manner to the brooder structure. Access to said runways may be had through the hinged covers 22 of all but the bottom compartments, each of the latter being provided with a hinged closure 23 in its vertical wall. The reason for this difference is that each bottom compartment does not extend beyond the runway of the compartment immediately above it, as clearly shown in Fig. 3.

The several compartments are ventilated through upright tubes 24 which are fitted over openings 25 in the combined floor and roof members 14 and extend up through the hinged covers 22 of the screened in runways. This applies to all of the compartments except the one at the top which is covered by the peaked roof illustrated in Fig. 6 and which comprises two sections 26 and 27 having tongue and groove connection 28 along the peak. This peaked roof has slotted ears 29 at its ends to engage headed lugs 30 on the inner faces of the end members. This top compartment is ventilated through a pipe 31 in the peaked roof. Said pipe 31 may be fitted with a cover 32 attached to a lever 33 intermediately pivoted at 34 and connected at its other end by rod 35 to a thermostat 36 suitably supported within said top compartment. It will be understood that the ventilating pipes 24 for the other compartments may also be fitted with covers controlled by thermostats in substantially the same manner. The curtains 20 for the top compartment are attached to the peaked roof, while the curtains for the lower compartments are connected to the combined floor and roof members.

All of the compartments except the top ones, which have considerably smaller floor space than the others, may be provided with transverse partitions 37, Fig. 10, preferably made of wire mesh material and retained in place by grooves 38 on the combined floor and roof members 14. These partitions 37 may extend across the runways beyond the curtains as well as across the inclosed portions of the compartments. 75

The several compartments are heated from the tunnel 10 by means of a hot air pipe 39 extending through the upper portion thereof above the door openings 5. Heated air is supplied to this pipe 39 from a burner 80 or lamp 40 arranged in a casing 41 on the outside of the brooder and connected to said pipe 39 by an elbow pipe 42 hinged thereto at 43, so that the elbow may be swung upward for inspecting the burner without disconnecting it from the pipe 39. As shown, the burner is adapted to be supplied with fuel from a tank 44, the supply being controlled by a valve 45. The heated air after passing through the pipe 39 in the tunnel is permitted to slowly escape through a restricted outlet pipe 46 protruding from the end of the brooder and preferably provided with an adjustable cap 47.

The heated air passes from the tunnel to the two bottom compartments of the brooder through slots 48 formed in or near the lower edge of the tunnel walls. The upper compartments are supplied with heated air from the tunnel through openings 49 in the tunnel 100 walls, separate openings being provided for the compartments at opposite sides of the partitions 37. The passage of the heated air through these openings 49 is automatically controlled by dampers 50 intermediately pivoted at 51 on the inside of the tunnel and connected by means of straps 52 with a thermostat 53 arranged in the lower portion of the tunnel. If some of the compartments are not in use, the straps 52 may 110 be disconnected from the corresponding dampers, and the latter kept closed, whereby only the amount of heat necessary to warm the occupied compartments need be furnished. 115

The thermostat 53 may be of any known construction. As shown, it is composed of a looped bar having an extension rod 58 at one end pivoted at 54 to one wall of the tunnel while the other end of said looped bar 53 is 120 connected to a rod 55 which is pivoted at one end to one of the straps 52 at 56 and at the other end to the other strap 52 at 57, Figs. 3 and 9. The strap on the side adjacent the pivot 54 is also pivoted at 59 to 125 the extension rod 58, so that when said loop expands under the action of the heated air in the tunnel the rod 55 will be forced downward carrying with it both of the straps 52 which are connected to its opposite ends, 130

thereby simultaneously swinging all of the dampers 50 on their pivots 51 to close the openings 49. The strap 52, which is connected to the extension rod 58, is permitted 5 to move downward when the thermostat 53 expands by reason of the pivots 54 and 59. When the temperature falls to a suitable degree, the thermostat will act to cause the dampers to swing in the opposite direction 10 and uncover the openings 49.

The tunnel is preferably divided by a transverse partition 60 which may be supported in position in line with the partitions 37 by downwardly extending pins 61 engaging socketed lugs 62 on the inside of the tunnel. This partition preferably terminates below the heating pipe 29, as shown in Fig. 3.

In Figs. 12 and 13, I have shown a modified construction of the ends of the peaked roof 27 to provide for connecting an extension roof, as when two brooders are to be placed together, without duplicating the end members. As illustrated in these figures, 25 is the common end member of the two brooders or of the main brooder and extension, and 63 and 64 are the peaked roofs thereof. The roof 63 extends over the end member 2 and is bent to form a groove 65 into which a flange 66 on the roof 64 fits for locking the two roofs together. The tongue and groove connections 67 and 68 of the roofs 63 and 64, which are similar to the tongue and groove connection 28 along the 35 peak of the roof 27, simply abut, as shown in Fig. 12, the grooves 65 being formed in the inclined portions of the roof 63 at opposite sides of the tongue and groove connections 67 at the peak.

40 It will be observed that a considerable number of separate compartments are provided in a single brooder structure by means of the combined floor and roof members 14 and the partitions 37, thereby providing for 45 housing many different broods of chicks, each of which has a separate runway open to the outside air. The heating of all except the two bottom compartments is controlled by the thermostat-actuated dampers, 50 so that too much heat will not be furnished to the upper compartments and not enough to the bottom compartments. Of course, the greater portion of the heat will collect in the upper portion of the tunnel, and for this 55 reason the slots 48 in the lower edge of the tunnel walls are always left open to permit a sufficient amount of heated air to pass to the bottom compartments.

Having thus described my invention, 60 what I claim as new and desire to secure by Letters Patent of the United States is:—

1. A brooder having a plurality of compartments arranged one above the other in stepped relation, separate outside runways 65 for said compartments, the runways for the

upper compartments being arranged on the projecting portions of the roofs of the lower compartments, said projecting portions of the roofs having openings therein, and separate ventilating pipes fitted over said openings and extending up through said runways. 70

2. A knockdown brooder comprising end members having horizontal grooves in their inner faces and vertical grooves at their edges, combined floor and roof members having their lateral edges arranged in the horizontal grooves, whereby the brooder is divided into a plurality of compartments arranged one above the other, and depending flanges on said combined floor and roof members engaging the vertical grooves at the edges of the end members. 75

3. A knockdown brooder comprising end members having stepped edges, horizontal grooves on their inner faces in line with the tops of said steps, and vertical grooves at the ends of the steps, combined floor and roof members having their lateral edges arranged in the horizontal grooves of the end members, whereby the brooder is divided into a plurality of compartments arranged one above the other, and depending flanges on said combined floor and roof members engaging the vertical grooves at the ends 95 of the steps in the end members.

4. A knockdown brooder comprising end members having grooves in their inner faces, a tunnel member having headed lugs on its outer faces, combined floor and roof members having their lateral edges arranged in the grooves in the end members, whereby the brooder is divided into a plurality of compartments arranged one above the other, and flanges on said combined floor and roof members, said flanges having slots adapted to engage said headed lugs. 100

5. A brooder having a tunnel dividing it into separate compartments and provided with openings in its opposite walls 110 communicating with said compartments, dampers adapted to cover said openings, means for heating the air in the tunnel, a thermostat in the tunnel and means of connection between the thermostat and dampers 115 for simultaneously moving the dampers at both sides.

6. A brooder divided into a plurality of compartments arranged one above the other, a tunnel extending through the brooder and 120 provided with openings in its opposite walls communicating with the several compartments, dampers mounted on the walls of the tunnel to cover said openings, straps connecting the dampers on the respective sides 125 of the tunnel, and a thermostat connected to both straps for simultaneously moving all the dampers.

7. A brooder divided into a plurality of compartments arranged one above the other, 130

a tunnel extending through the brooder and provided with openings communicating with the several compartments, the openings leading to the bottom compartments being uncovered, controllable means for covering the openings leading to the upper compartments, and a heating pipe extending through the upper portion of said tunnel from one end of the brooder to the other.

10 8. A brooder comprising end members having door openings therein, a tunnel ex-

tending between said end members in line with said door openings, the top of the tunnel projecting above said openings, and a heating pipe supported by the end members in the upper part of the tunnel, there being openings in the walls of the tunnel for delivering the heated air from the tunnel to the brooder.

In testimony whereof I have signed my name to this specification.

ERWIN MAURER.
